J. R. ROSE AND EDWARD L. CALEY, OF PHILADELPHIA, PENNSYLVANIA
ASSIGNORS TO COX, WHITEMAN, AND COX, OF SAME PLACE.

Design No. 3,015, dated May 5, 1868; antedated April 7, 1868.

DESIGN FOR A FIRE-CYLINDER CAP FOR A STOVE.

The Schedule referred to in these Letters Patent and making part of the same.

TO ALL WHOM IT MAY CONCERN:

Be it known that we, J. R. ROSE and EDWARD L. CALEY, carvers, of the city of Philadelphia, and State of Pennsylvania, have invented or produced a new and original Design for the Fire-Cylinder Cap, with Illuminating Fire-Door and Windows for a Stove; and we do hereby declare that the following is a full, clear, and exact description of the same, reference being had to the accompanying drawing, making a part of this specification, and to the letters of reference marked thereon.

Our design consists in the two ornamental mouldings, A A and B B, with the ornamental configuration and openings between them, as shown.

What we claim as our invention, and desire to secure by Letters Patent, is—

The ornamental design herein described and shown.

J. R. ROSE,
EDW. L. CALEY.
